UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF NEW JERSEY.

TYPE-WRITING MACHINE.

1,021,970.

Specification of Letters Patent.

Patented Apr. 2, 1912.

Application filed January 19, 1910. Serial No. 538,837.

To all whom it may concern:

Be it known that I, CORNELIUS B. CORCORAN, a citizen of the United States, residing in the borough of Bronx, city of New York, in the county of New York and State of New York, have invented certain new and useful Improvements in Type-Writing Machines, of which the following is a specification.

10 This invention relates to devices employed in typewriting machines for releasing the platen from the line-space wheel, so that the platen may be freely turned while the line-space wheel is held stationary by 15 the usual spring detent.

One of the main objects of this invention is the provision of a positive lock for this purpose, which will convert these parts practically into a single rigid structure, in 20 capable of relative rotation.

I have provided clutch members which positively interlock. One member of the clutch is equipped with perforations or other seats engaged by a tooth or teeth on a 25 coöoperating clutch member. The teeth, bolts or dogs are mounted upon a carrier which is connected to said finger-piece and is capable of rotation caused by its sliding movement, when the finger-piece is pushed 30 inwardly. In case the bolts strike against the septa between the perforations, they will nevertheless continue to turn until they register with the perforations, whereupon 35 they are snapped into said perforations by springs, to lock the platen again to the line-space wheel.

Other objects and advantages will herein-after appear.

In the accompanying drawings, Figure 1 40 is a plan view partly broken away to show the application of my invention to an Underwood typewriting machine. Fig. 2 is a detail cross sectional view, showing the positions assumed by the parts when the platen is released from the line-space wheel. Fig. 3 is a fragmentary view, partly in 45 cross - section, showing the positions of the parts when the bolts of the loose clutch member are in engagement with the septa 50 between the seats in the fixed clutch member. Fig. 4 is a similar view showing the normal positions of the parts, the platen and line-space wheel being rigidly connected. Fig. 5 is a detail side view of one 55 of the locking dogs. Fig. 6 is a detail cross-

sectional view, taken at right angles to Fig. 3, showing the positions of the bolts engaging the septa between the seats in the fixed clutch member. Fig. 7 is an end view partly in section, showing the releasing head 60 controlling the clutch mechanism. Fig. 8 is a perspective view partly broken away, showing the operative parts of the invention disassembled.

The usual platen 1 is secured to an axle 2 65 journaled in a platen frame 3. A toothed line-space wheel 4 engaged by a spring detent 5, is operated by a lever 6 through a slide 7 and pawl 8 to effect the line-spacing of the platen. The line-space wheel is 70 shown in the form of a drum 9 carrying the teeth 4, and loose on the axle 2. A finger-piece 20 is connected to slide a releasing head 16 in the axle 2 to withdraw bolts 12 from perforations 11 in a disk 10 fixed to 75 the platen or axle 2. The bolts are mounted in a carrier 13 connected with the line-space wheel, so that the withdrawal of the bolts releases the platen from the line-space wheel. After the platen 1 is adjusted in the 80 usual manner, the finger-piece 20 is released, whereupon a spring 26 moves the releasing head inwardly 16. Provision is made to render the platen universally adjustable, or in other words, to engage the bolts in the 85 perforations 11 of the disk 10 at any adjustment of the platen 1 and its disk 10. This is done by giving the bolt-carrier 13 a slight turning movement around the platen axle 2. For this purpose, the bolt-carrier is 90 connected to the line-space wheel 4 by followers 14 and inclined grooves or cams 15, which, when the bolt-carrier slides along the platen axle, turn the carrier with its bolts relatively to both platen and line-space wheel. Should the bolts strike the 95 septa between the perforations 11, the bolt carrier will nevertheless continue to turn until the bolts register and snap into the holes. By the employment of the bits or followers 14 working in the helical or inclined slots 15, the carrier and its bolts are turned around the platen axle to secure the necessary registration. The bolts are 100 slideable endwise in the bolt carrier 13, as well as in the releasing head 16, thus permitting the carrier 13 to move independently when returning, so that the bolt carrier may not be arrested by the striking of the bolts against 105 the septa.

The bolt carrier 13 is loosely connected to the releasing head by guide pins 18, which permit relative sliding or axial movement between head 16 and carrier 13, to enable the bolt or bolts 12 to be released prior to the movement of the bolt carrier. The releasing head 16 may also move inwardly, to set the bolts toward the perforations, prior to the return movement of the bolt carrier. The screw or helical motion of the bolt carrier 13 is communicated to the releasing head 16 which is loose on the axle 2, the finger piece 20 being connected thereto by a stem 21, projecting beyond the usual finger-knob 22 fixed on the outer end of the axle 2, which is hollow to accommodate the stem. The latter has a bit 23 fitting in and projecting from a longitudinal slot 24 in the axle, into an annular groove 25 in the releasing head 16. This permits free rotation of the releasing head with the bolt carrier.

To permit the operator to use both hands in adjusting the platen and paper, a detent is provided to hold the clutch disengaged, comprising a spring-pressed ball 27 taking into a seat or recess 29, on the stem 21. The ball is located in a socket in the finger knob 22 and pressed against the stem 21 by a spring 30 held in place by a screw 31. When the catch is in recess 28, it holds the stem steady against accidental outward movement.

The inclined or helical slots 15 in the drum should be long enough to turn the bolt carrier through an arc substantially equal to the distance between the centers of two adjacent seats 11, and are inclined but slightly. Often a less turning movement than this will be sufficient to register the bolts and seats; and since a further pressure on the stem 21 would push in the carrier, and thereby turn the platen (because of the cam action between the bolt carrier and drum), which would impair the adjustment just obtained, I provide dogs or locks for arresting the bolt carrier, or for securing the parts together, simultaneously with the seating of the bolts. This lock includes a pair of opposite dogs 33 mounted in the bolt carrier to slide into and out of engagement with the inner surface of the drum, which at this point may be interiorly roughened or knurled, as at 34, to prevent slipping of the dogs or jaws. The dogs are projected outwardly into engagement with opposite sides of the drum, at the moment when the bolts seat in the clutch member 10, by means of elbow-levers 35 pivoted on a ring 36 mounted loosely on the platen axle, and having a pin or key 37 engaging a groove 38 in the axle. One arm 35^a of the elbow lever is inserted in a slot 39 in the bolt. The other arm 35^b of the lever passes through an aperture 40 in the bolt carrier and enters an

opening 41 in the dog. When the bolts snap into the holes 11, the elbow levers will be rocked to throw the dogs 33 out into engagement with the drum 9, to prevent further movement of the bolt carrier. The withdrawal of the bolts rocks the elbow levers in the opposite direction, to retract the dogs and permit the bolt carrier to be drawn outward by the releasing head. The dogs may be each bifurcated, as shown at 42, (Fig. 5). Though I have shown a plurality of bolts, the device is operative when a single bolt is employed.

The finger piece 20 withdraws the bolts 12 and the bolt carrier 13 successively, the latter making an idle rotation due to its screw coupling with the line-space wheel. In reengaging the clutch, the bolts are set toward the fast clutch member and followed by the bolt carrier, which turns as it is pushed back again to register the bolts with the perforations, the springs 19 snapping the bolts into the perforations. By providing a large number of seats 11, the arc through which the bolt carrier must be turned in alining the bolts and seats is reduced.

Having thus described my invention, I claim:

1. In a typewriting machine, the combination with a platen, a line-space wheel relatively to which the platen turns, a detent for the wheel and line-spacing mechanism for turning the wheel, of a clutch mechanism for positively and rigidly connecting the line-space wheel and platen, including a clutch member fixed to turn with the platen, a coöperating clutch member connected with the line-space wheel, the platen capable of rotation relatively to said coöperating clutch member, a bolt loosely mounted in one of the clutch members for back and forth movement relatively to the remaining clutch member, to releasably connect the platen and line-space wheel, and releasing mechanism operable against the tension of a returning spring for effecting the disengagement of the bolt from the fast clutch member to permit the rotation of the platen relatively to the line-space wheel.

2. In a typewriting machine, the combination with a platen, a line-space wheel rotatable relatively thereto, a detent for the wheel, and line-space mechanism for turning the wheel, of a clutch mechanism for positively and rigidly connecting the platen and line-space wheel against independent rotation, including a clutch member fixed to turn with the platen and having seats therein, a loose clutch member having a screw coupling with the line-space wheel to afford the loose clutch member a limited turning movement relatively to both the platen and line-space wheel, a bolt mounted for back and forth movement in the loose

- clutch member to releasably connect the clutch members, releasing mechanism to control the engagement and disengagement of the clutch members, the releasing mechanism affecting the loose clutch member to cause a slight rotation thereof relatively to the platen and line-space wheel to aline the bolt with a seat in the fixed clutch member, and a spring for seating the bolt. 5
- 10 3. In a typewriting machine, the combination with a platen and its axle, a line-space wheel rotatable on the axle, a detent for the wheel and line-space mechanism for turning the wheel, of a clutch mechanism for positively and rigidly connecting the platen and line-space wheel releasably together, including a clutch member fixed on the axle, a bolt carrier loose on the axle and connected with the line-space wheel, a 15 bolt mounted in the bolt carrier and movable to lock the fixed clutch member to the line-space wheel, one end of the axle being hollow and having a slot therein, a releasing head connected to the bolt and sliding 20 on the axle, the releasing head having an annular groove communicating with the slot in the hollow axle, and a stem in the hollow axle, terminating in a button at its outer end, and carrying a bit projecting 25 through the slot in the axle into the annular groove in the releasing head, to control the position of the releasing head to effect the engagement and disengagement of the clutch members. 30
- 35 4. In a typewriting machine, the combination with a platen having an axle hollow at one end, a line-space wheel relatively to which the platen turns, a detent for the wheel, and line-space mechanism for turning the wheel, of a clutch mechanism for connecting the platen and line-space wheel, including a clutch member fixed to turn with the platen, a coöperating clutch member connected with the line-space wheel and 40 having a bolt releasably engaging the fixed clutch member, a spring-pressed releasing head for effecting the engagement and disengagement of the bolt and fixed clutch member, the releasing head capable of longitudinal and rotary movements on the axle, and a finger-operated stem slidable in and 45 out of the hollow axle and connected with the releasing head for operating the latter. 50
- 55 5. In a typewriting machine, the combination with a platen, a line-space wheel relatively to which the platen turns, a detent for the wheel, and line-space mechanism for turning the wheel, of a clutching mechanism for connecting the platen and 60 line-space wheel, including a clutch member fixed to turn with the platen and having a plurality of seats arranged circularly thereof, a bolt-carrier connected with the line-space wheel and having a spring-pressed bolt movable endwise in the carrier 65
- toward and from the fixed member, releasing mechanism controlling the engagement and release of the bolt from the fixed member, the bolt carrier being connected with said releasing mechanism to be moved back and forth, and a cam and follower connection between the bolt carrier and line-space wheel effective to turn the bolt carrier relatively to the fixed clutch member, as it is pushed toward the latter to register the bolt with a seat in said fixed clutch member. 70
- 75 6. In a typewriting machine, the combination with a platen and a line-space wheel relatively to which the platen turns, a detent for the line-space wheel, and line-space mechanism for turning the wheel, of two clutch members for positively and rigidly connecting the platen and line-space wheel, one of the clutch members comprising a perforated disk and the other clutch member having a bolt, one clutch member being fixed to turn with the platen, and the other being connected to the line-space wheel, one of the clutch members being slidable toward and from the other, and having a limited turning movement relative thereto, to register the bolt relatively to a perforation, and a releasing mechanism to control the engagement of the bolt with and its withdrawal from the perforation. 80
- 85 7. In a typewriting machine, the combination with a platen and a line-space wheel relatively to which the platen turns, a detent for the line-space wheel, and line-space mechanism for turning the wheel, of two clutch members for positively and rigidly connecting the platen and line-space wheel, one of the clutch members comprising a perforated disk and the other clutch member including a carrier slidable toward and from the disk, a bolt slidable in the carrier, to be projected into and withdrawn from a seat in the disk, a releasing mechanism connected to turn with the bolt carrier, and having a limited back and forth movement relatively thereto and to the bolt to advance the bolt and carrier toward and retract them from the disk, a screw coupling between the carrier and line-space wheel effective to turn the bolt-carrier and bolt relative to both the disk and line-space wheel to register the bolt with a seat, a spring for projecting the bolt into its seat and a lock operated by the bolt as it seats, effective to rigidly connect the line-space wheel and carrier. 90
- 95 8. In a typewriting machine, the combination with a line-space wheel, a platen rotatable relatively thereto, a detent for the wheel, and line-space mechanism for turning the wheel, of a clutch mechanism for connecting the platen and line-space wheel, including a clutch member fixed to rotate with the platen, and having a series of circularly arranged seats, a bolt movable to- 100
- 105 110 115 120 125 130

ward and from the fixed clutch member to enter one of the seats, a finger-piece for setting the bolt toward and withdrawing it from the seat, and a screw or helical connection between the bolt and line-space wheel effective to revolve the bolt around the platen axle relatively to the fixed clutch member through a limited arc to register it with a seat subsequently to its movement 10 toward said fixed clutch member.

9. In a typewriting machine, the combination with a line-space wheel, a platen rotatable relatively thereto, a detent for the wheel, and line-space mechanism for turning the wheel, of a clutch mechanism for connecting the platen and line-space wheel, including a clutch member fixed to rotate with the platen and having a plurality of seats, a bolt, a finger-piece effective to move 15 the bolt toward and from the fixed clutch member, to engage and withdraw it from one of the seats, and a screw or helical coupling between the bolt and line-space wheel effective to operate the bolt across the 20 face of the fixed clutch member, subsequently to the movement of the bolt toward the fixed clutch member, to register the bolt with a seat.

10. In a typewriting machine, the combination with a line-space wheel, a platen rotatable relatively thereto, a drum on the line-space wheel, a detent for the wheel, and line-space mechanism for turning the wheel, of a clutch mechanism for connecting the 25 platen and line-space wheel, including a clutch member fixed to rotate with the platen and having a plurality of seats, a bolt-carrier free to rotate on the axle and to slide back and forth relatively to the fixed clutch 30 member, a bolt mounted in the bolt carrier, a finger-piece controlling the movement of the bolt and carrier toward and from the fixed clutch member, the drum on the line-space wheel having an inclined or helical 35 cam slot, and a follower on the bolt carrier engaging the walls of said slot for camming the bolt into register with one of the seats in the fixed clutch member.

11. In a typewriting machine, the combination with a platen, a line-space wheel relatively to which the platen turns, a detent for the wheel, and line-space mechanism for turning the wheel, of a clutch mechanism for connecting the platen and line-space 45 wheel, including a clutch member fixed to turn with the platen and having a plurality of seats arranged circularly thereof, a bolt-carrier connected with the line-space wheel and having a spring-pressed bolt movable 50 endwise in the carrier toward and from the fixed member, releasing mechanism controlling the engagement and release of the bolt with the fixed member, the bolt carrier being connected with said releasing mechanism 55 to be moved back and forth, a cam and fol-

lower connection between the bolt carrier and line-space wheel effective to turn the bolt carrier relatively to the fixed clutch member, as it is pushed toward the latter to register the bolt with a seat in said fixed clutch member, and a lock effective to arrest the advance of the bolt carrier toward the fixed clutch member when the bolt seats itself. 70

12. In a typewriting machine, the combination with a platen, a line-space wheel relatively to which the platen turns, and having a drum, a detent for the wheel, and line-space mechanism for turning the wheel, of a clutch mechanism for connecting the platen and line-space wheel, including a disk fixed to turn with the platen and having a plurality of seats, a bolt-carrier free to turn relatively to, and to slide toward and from the fixed disk, a bolt mounted in the bolt-carrier for endwise movement toward and from the fixed disk, and normally tending to seat itself in the disk, a finger piece controlling the setting of the bolt and bolt-carrier toward and their withdrawal from the disk, a helical coupling between the bolt-carrier and the line-space wheel for turning the bolt-carrier and bolt to register the latter with a seat in the fixed disk, as the carrier is set toward the disk, and a dog mounted in the bolt-carrier to bite on the drum of the line-space wheel when the bolt is entered in its seat. 75 80 85 90

13. In a typewriting machine, the combination with a platen, a line-space wheel relatively to which the platen turns, and having a drum, a detent for the wheel, and line-space mechanism for turning the wheel, of a clutch mechanism for connecting the platen and line-space wheel, including a disk fixed to turn with the platen and having a plurality of seats, a bolt-carrier free to turn and slide relatively to the fixed disk, a bolt mounted in the bolt-carrier for movement toward and from the fixed disk, and normally tending to seat itself in the disk, a finger piece controlling the setting of the bolt and bolt-carrier toward and their withdrawal from the disk, a helical coupling between the bolt-carrier and the line-space 100 105 110 115 120 wheel for turning the bolt-carrier and bolt to register the latter with a seat in the fixed disk, as the carrier is set toward the disk, and a dog mounted in the bolt-carrier and operated by the movement of the bolt into its seat, the dog being effective to bite on the roughened inner surface of the drum to arrest the set of the bolt-carrier toward the fixed disk. 125

14. In a typewriting machine, the combination with a platen, a line-space wheel relatively to which the platen turns, and having a drum, a detent for the wheel, and line-space mechanism for turning the wheel, of a clutch mechanism for connecting the 130

- platen and line-space wheel, including a disk fixed to turn with the platen and having a plurality of seats, a bolt-carrier free to turn and slide relatively to the fixed disk, 5 a bolt mounted in the bolt-carrier for movement toward and from the fixed disk, and normally tending to seat itself in the disk, a finger piece controlling the setting of the bolt and bolt-carrier toward and their withdrawal from the disk, a screw or helical coupling between the bolt-carrier and the line-space wheel for turning the bolt-carrier and bolt to register the latter with a seat in the fixed disk, as the carrier is set toward 10 the disk, a dog mounted in the bolt-carrier, an elbow lever pivoted on a support turning with the bolt-carrier, one arm of the elbow lever connected with the bolt, the opposite arm of the lever operating the dog and effective to throw the latter outward to bite on the drum as the bolt enters its seat. 15 In a typewriting machine, the combination with a platen, a line-space wheel relatively to which the platen turns, a detent for the wheel, a line-space mechanism therefor, of a clutch mechanism for positively connecting the line-space wheel and platen, including a disk fixed to turn with the platen and having a plurality of seats 20 therein, a bolt-carrier rotatable and slidable back and forth relatively to the disk, a spring-pressed bolt mounted for movement in the bolt-carrier, to engage one of the seats in the disk, a releasing mechanism with 25 which the bolt carrier is loosely connected for setting the bolt and bolt-carrier toward and withdrawing them from the fixed disk, locating mechanism for turning the bolt-carrier and bolt to register the bolt with one 30 of the seats, and locking mechanism operating with the engagement of the bolt into its seat to secure the bolt-carrier and line-space wheel together. 35 In a typewriting machine, the combination with the platen and its axle, a line-space wheel rotatable on the axle, a detent for the wheel and line-space mechanism for turning the wheel, of a clutch mechanism for positively and rigidly connecting the platen 40 and line-space wheel together, including a clutch member fixed on the axle, a bolt-carrier loose on the axle and connected with the line-space wheel, a bolt mounted in the bolt-carrier and movable back and forth to lock the fixed clutch member to and release 45 it from the line-space wheel, a rotatable releasing head connected to the bolt and slideable along the axle, and a slideable finger piece connected with the releasing head to 50 permit rotation of the latter relatively to the finger-piece, the finger piece effective to control the engagement and disengagement of the platen and line space wheel. 55 In a typewriting machine, the combination with a platen and a line-space wheel 60 relatively to which the platen turns, of a clutch mechanism for connecting the platen and line-space wheel including a clutch member connected to the platen and coöperating with a second clutch member connected with the line-space wheel, one of the clutch members having seats engaged by a spring-pressed bolt mounted in the coöperating clutch member, one of said clutch members mounted to slide toward and from the remaining clutch member and having a limited turning movement relatively to the platen and line space wheel to align the bolt and its seat, and a finger-piece to control the engagement and disengagement of the clutch members. 65 In a typewriting machine the combination with a line-space wheel and a platen adjustable relatively thereto, of a positive clutch for releasably connecting the line-space wheel and platen against relative movement, and including a clutch member having seats, and a coöperating clutch member having bolts slideable endwise relatively to their clutch member to engage and withdraw from the seats in the remaining clutch member, a finger-piece controlling the bolts, and having a limited endwise movement relatively thereto, springs tensioned by such endwise movement for seating the bolts when they are registered with their seats, one of the clutch members being secured to the platen, the remaining clutch member being slideable toward and from the platen and having a connection with the line-space wheel permitting a limited turning of the clutch member relatively thereto when it is pushed toward the platen to register the bolts with their seats. 70 In a typewriting machine the combination with a platen and a line-space wheel, of intermediate clutch members, one having seats, and the other having a bolt to engage said seats, said clutch members having a helical coupling, to afford a limited rotative adjustment. 75 In a typewriting machine the combination with a platen and a line-space wheel, of intermediate clutch members, a bolt mounted upon one clutch member, the other clutch member provided with seats, a returning spring for the bolt, and a finger piece having means to withdraw the bolt; said bolt being mounted for independent movement upon its clutch member, to permit the latter to move relatively to the other clutch member to bring the bolt 80 into register with a seat in the latter. 85 In a typewriting machine the combination with a platen and a line-space wheel, of an intermediate clutch member having seats, a coöperating clutch member loosely carrying a bolt, a finger-piece, a head connected to said finger piece and loosely engaging said bolt to withdraw the same from said seats, said head loosely connected to said bolt carrier to move the same away from said seats, and said bolt- 90 95 100 105 110 115 120 125 130

carrier capable of rotative adjustment relatively to said seats, independently of the platen and line-space wheel.

22. The combination with a platen and a line space wheel, of an intermediate clutch member having seats, a coöperating clutch member loosely carrying a bolt, a finger-piece, a head connected to said finger piece and loosely engaging said bolt to withdraw the same from said seats, said head loosely connected to said bolt carrier to move the same away from said seats, and said bolt-carrier capable of rotative adjustment relatively to said seats, independently of the platen and line-space wheel, and a spring for returning said head and bolt carrier and for effecting rotative adjustment thereof.
23. The combination with a platen and a line-space wheel, of intermediate clutch members, one having seats, and the other having a set of bolts to engage said seats, said clutch members having a helical coupling, to afford a limited rotative adjustment.
24. The combination with a platen and a line space wheel, of an intermediate clutch member having seats, a coöperating clutch member loosely carrying a set of bolts, a fin-

ger-piece, a head connected to said finger piece and loosely engaging said bolts to withdraw them from said seats, said head loosely connected to said bolt carrier to move the same away from said seats, and said bolt-carrier capable of rotative adjustment relatively to said seats, independently of the platen and line-space wheel.

25. The combination with a platen and a line space wheel, of an intermediate clutch member having seats, a coöperating clutch member loosely carrying a bolt, a finger-piece, a head connected to said finger piece and loosely engaging said bolt to withdraw the same from said seats, said head loosely connected to said bolt carrier to move the same away from said seats, and said bolt-carrier capable of rotative adjustment relatively to said seats, independently of the platen and line-space wheel, a spring for returning said head and bolt carrier and for effecting rotative adjustment thereof, and a lock.
